Primary Examiner — Michelle E. Wilson

Assistant Examiner — Caitlin A Laverty

(57) CLAIM

The ornamental design for a bag as shown and described.

DESCRIPTION

1. Bag
- 1.1 : Perspective
- 1.2 : Front
- 1.3 : Back
- 1.4 : Right
- 1.5 : Left
- 1.6 : Top
- 1.7 : Bottom

1. The use of the product to which each model applies is: Clothing for utilitarian (storage for small personal items) and aesthetic purposes; 2. The characteristic features of the design in the shape of the bag, as shown.

The broken lines in the drawings represent stitching that does not form part of the claimed design.

1 Claim, 7 Drawing Sheets
